UNITED STATES PATENT OFFICE.

HENRY TÖNSMANN, OF SAO PAULO, BRAZIL, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed March 29, 1924. Serial No. 702,856.

This invention relates to cash registers and is shown carried out in connection with a machine of the type shown in Letters Patent of the United States to Cleal and Reinhardt, No. 580,378, dated April 13, 1897, and Letters Patent to Cleal, No. 747,855, dated Dec. 22, 1903.

An object of this invention is to provide record material feeding mechanism which is under the control of depressible keys.

Another object is to provide a depressible key which may remain depressed for an indefinite number of operations of the machine and cause the record material feeding mechanism to issue receipts.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a side elevation of a machine showing the improvement added thereto.

Fig. 2 is a detail view of a portion of the improvement.

Fig. 3 is a detail end view of the feeding rollers with the lower adjustable roller in feeding relation with the upper roller.

Fig. 4 is a detail view of the release key.

The invention is shown as carried out in connection with a key-set, crank or motor operated machine, equipped with a printing mechanism for issuing receipts under control of manipulative means. It comprises the usual amount banks for setting up printing elements, etc., neither of which is disclosed herein. It also comprises a main driving shaft 20 suitably journaled in the side frames of the machine, the left hand frame is shown at 21 in Fig. 1. This shaft is driven from the crank or motor, as the case may be, and actuates the printing mechanism, etc., to which this invention relates.

There are three special transaction keys 22 suitably mounted in the frame member 21, any one of which when depressed will cause a printing mechanism to issue a printed receipt, all of which is well known in the art and fully described in the patents previously referred to.

Each key 22 has a pin 23 which, as the

key is depressed, will engage an angle edge 24 on a detent plate 25 and move the detent upward against the tension of a spring 26 until the pin is opposite to the vertical opening 27, when the detent will be returned to normal position by the spring, and will retain the key in the depressed position until released during an operation of the machine. The detent plate 25 is bifurcated at each end to engage screw studs 28 and 29 by which it is guided in its movements.

The means for releasing the keys during an operation of the machine comprises means for raising the detent plate 25. Extending downwardly from the lower end of the detent plate is an arm 30 carrying a pin 31 which engages an angle notch 32 in the upper edge of a slide 33. The slide is guided at its right hand end by a pin 34 and at the left hand end by an oscillating shaft 35. Secured to the end of the oscillating shaft 35 by a screw 36, is a cam plate 37 which cooperates with a roller 38 carried on the slide 33 to move the slide toward the right at each operation of the machine and cause the detent plate 25 to move upward and release the depressed key 22. The pitman 33 is returned to normal position by a spring 39.

The keys 22 are returned to normal position and held there by springs 40 as usual. The receipt printing and issuing mechanism is controlled from the special transaction keys 22 and a receipt key to be hereinafter described. With any one of the above mentioned keys in their depressed position the receipt feeding rollers will feed the record material through the printer to issue a printed receipt.

When a key 22 is depressed, its pin 23 engages a curved edge 45 of a plate 46 slidably mounted on a pitman 47 by two studs 48 fitted to elongated openings 49. The sliding plate 46 is held in its normal position by a spring 50, one end of which is attached to the upper corner of the plate and the other end to a pawl 51 loosely mounted on a screw stud 52 fastened in a plate 53 which is secured to the side frame by the screws 28 and 29.

The sliding plate 46 is provided with a notch 54 which, when said plate is moved by depressing one of the keys 22, will be in position to permit a projection 55 on a pawl 56 to enter the notch during the operation

of the machine. The pawl 56 is pivoted at 57 to a reciprocating plate 58 and has a pin 59 normally engaging a shoulder 60 on a lever 61, under tension of a spring 62. As 10 the lever 61 moves clockwise, the pin 59 will continue to rest upon the shoulder 60 until the projection 55 enters the notch 54, after which the lever continues its movement with its inclined edge 63 engaging a roller 64 carried by the reciprocating plate 58 thereby causing said plate to move toward the left against the tension of a spring 65 which will return the plate to normal during a counter-clockwise movement of the lever 61. The 15 plate 58 is slidably supported on two pins 66 which project from the pitman 47 into elongated openings 67 in the plate.

As the projection 55 on the pawl 56 enters the notch 54 it will also enter a notch 72 in 20 the pitman 47. With the pawl 56 in the notches 54 and 72, the pitman 47 and plate 46 will move in unison with the reciprocating plate 58 when the lever 61 moves clockwise. The lever is operated from the driving shaft 20 by a cam 73 secured thereto, which cooperates with a roller 74 carried by the lever. The lever is pivoted on a pin 75 supported in the side frame. The roller 74 is maintained in engagement with the 25 cam 73 by a spring 76.

The operation of the pitman 47 controls the feeding of record material by the feeding rollers 77 and 78. The left hand end of the pitman is connected to an arm 79 30 clamped to a rod 80 upon which is securely mounted an eccentric bearing 81 for the roller 77. In its normal position the roller 77 will not engage a flange 82 formed on the roller 78 as the rollers are operated, and 35 therefore record material which extends between these rollers will not be fed along with the rollers in normal position. But when the eccentric bearing 81 is moved clockwise by the pitman 47, the roller 77 40 will engage the flange 82 with the record material between the roller and the flange and feed the record material through the printing mechanism in the usual way. The roller 78 is suitably geared to the main drive 45 shaft and in turn drives the roller 77 by means of gears as shown in Fig. 3. These gears are never entirely out of mesh with each other regardless of the adjusted position of the bearing 81.

50 In addition to the three special transaction keys 22 there is a receipt key 86 which also operates the record material feed controlling mechanism. This key is adapted to remain in the depressed position for an indefinite number of operations of the machine, the machine issuing a receipt at each operation while the key is in the depressed position.

The receipt key 86 is supported on the 55 plate 53 by three studs 87 which are pro-

vided with heads overlapping the key. The lower end of a lug 88 secured to the key 86 engages the curved edge 45 of the plate 46 to move the plate to the same extent as the keys 22, hereinbefore described. When the key 86 is in its home position a projection 89 on the spring actuated pawl 51 engages a notch 90 in the flange part of the key and when the key is in its depressed position the projection 89 engages a second 75 notch 91. The lower lip of the notch 90 extends out from the key so as to engage the projection 89 as the key returns to its home position. The counter-clockwise movement of the pawl 51 is limited by the pawl engaging the left hand key guide stud 87.

The receipt key 86 will remain in the depressed position until released by a manually operated release key 92 (Figs. 1 and 4). This release key is retained in normal position by a spring 93. In depressing the release key a flange 94 on the lower end of the key engages the pawl 51 and disengages the projection 89 from the notch 91, allowing the key 86 to return to normal position by the spring 50 moving the plate 46 toward the right.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which 100 follow.

What is claimed is:

1. In a machine of the class described, the combination of record material feeding rollers normally ineffective with one roller having a movable bearing adapted to be moved to make said rollers effective, a pitman connected to and adapted to move said bearing, a driving member, a lever operated by said driving member, a reciprocating member operated by said lever member, a latch member carried by said reciprocating member and retained in its home position by said lever, a 105 depressible key returned to home position during the operation of the machine, and a movable member operated by said key and adapted to permit said latch to engage said pitman and move said feeding roller into effective feeding position.

2. In a machine of the class described, the combination of a pair of record material feeding rollers normally ineffective with one roller having a movable bearing adapted to be moved to make said rollers effective, a pitman connected to and adapted to operate 120 said movable bearing, a plate slidably supported on said pitman, a latch member carried by said sliding plate and adapted to engage said pitman to cause said sliding plate and said pitman to move in unison, a 125

driving means adapted to operate said sliding plate, a second plate slidably supported on said pitman to normally prevent said latch engaging said pitman, and depressible keys adapted to move said second sliding plate to permit said latch member to engage said pitman.

3. In a machine of the class described, the combination of a pair of record material feeding rollers normally ineffective, a movable bearing for one of said rollers adapted to be moved to make said rollers effective, a pitman connected to said movable bearing, a plate slidably supported on said pitman, a

latch member carried by said sliding plate 15 and adapted to engage said pitman to cause said sliding plate and said pitman to move in unison, a driving means adapted to operate said sliding plate, a second plate slidably supported on said pitman to normally 20 prevent said latch from engaging said pitman, a depressible key adapted to move said second sliding plate to permit said latch member to engage said pitman, and means for retaining said key in depressed position 25 indefinitely.

In testimony whereof I affix my signature.

HENRY TÖNSMANN.
